UNITED STATES PATENT OFFICE.

WILLIAM W. GILMAN, OF SAN FRANCISCO, CALIFORNIA.

PRINTER'S GALLEY.

SPECIFICATION forming part of Letters Patent No. 359,208, dated March 8, 1887.

Application filed March 20, 1886. Serial No. 196,025. (Model.)

To all whom it may concern:

Be it known that I, WILLIAM W. GILMAN, a citizen of the United States, residing at San Francisco, in the county of San Francisco and 5 State of California, have invented a new and useful Improvement in Printers' Galleys, of which the following is a specification.

My invention relates to improvements made in respect to the operating of side-sticks of 10 printers' galleys from a standpoint more or less distant from the matter to be held locked therein.

My improvements consist in certain novel 15 construction and arrangement of the side-stick connected to a side plate of the galley-frame by pivoted swinging arms, and a slotted plate operating upon the side-stick, whereby a parallel position equidistant of the side-stick with the side rail of the galley is always 20 maintained, and to an easy means for operating and holding the side-stick in the desired position.

The construction, application, and operation of these parts are fully explained in the 25 following description, the accompanying drawings, referred to by figures and letters, forming a part hereof.

Figure 1 represents a plan or top view of my improved printer's galley. Fig. 2 is a 30 side view of the same. Fig. 3 is a cross section.

Similar letters refer to similar parts throughout the several views.

The base-plate A of my printer's galley is made of one sheet of metal and of a sufficient 35 width to receive and hold a side rail, B, which latter may be constructed of wood. A plate, C, bent at a right angle, incloses a portion of the bottom and the inner face of the rail B. The wooden rail B also extends at a right angle 40 across one end of the galley, and has its seat in an angle-plate similar to the plate C of the side rail hereinbefore mentioned. These angle-plates are all secured to the base-plate by screws, and to the outer edge of the base-plate 45 is connected a strip of metal or plate, D, by brazing or otherwise, in such a manner as to make a secure joint. The inner edge of this plate is beveled, and the plate is of considerable thickness, so as to elevate the swinging 50 arms E E E sufficiently to enable them to be

conveniently connected with the side-stick in such a manner as to move freely and out of contact with the base A, said arms E being pivoted upon the top of the strip D.

The side-stick is composed of a T-shaped 55 piece of metal, F, and the inner end thereof is provided with a projection or hooked lug, G, which moves in a slot, G*, of the vertical plate H, set edgewise at the head of the galley-frame. Over the side-stick is placed a sliding 60 plate, I, slotted at I*, which is pivoted to the swinging arms E by the pins or set-screws J, which latter also pass through the side-stick. The sliding plate moves upon a set-screw, K, which enters the side-stick and limits the 65 throw of the sliding plate when it is carried backward or forward upon the face of the side-stick.

In practice, and when requisite to move the side-stick toward or away from the side rail 70 of the galley, the compositor places his thumb or fingers upon the projecting lug L and moves the sliding plate outward or backward, as the case may require, upon the side-stick, limiting its movement by the slot and set-screw, 75 and carrying the side-stick with it, which causes the pivoted swinging arms to assume a greater or less degree of inclination and maintain a true parallelism of the side-stick equidistant from and with the side rail of the galley, while the swinging arms will be gradually 80 closed up under the side-stick, between it and the side strip or plate, D. Thus it will be seen that a true parallelism of the side-stick equidistant with the side rail of the galley can be 85 attained and the side-stick be held firmly at any necessary point by the set-screw to accommodate the different sticks of matter from the compositor's hand, which matter can be easily and quickly locked up by the foot lock-up M, 90 and kept from being pied or disturbed when the side-stick is moved to add new matter to the galley.

Having thus described my invention, what I claim, and desire to secure by Letters Patent, is—

1. The combination, with the galley-frame, of a slotted side-stick carrying a slotted sliding plate, held in position thereon by suitable means, as described, and the swinging arms 100

pivoted to the sliding plate, and likewise to the side of the galley-frame, so as to operate substantially as set forth.

2. The combination of the galley-frame provided with the strip D, the slotted side-stick, the slotted sliding plate carried thereon and held in place by a set-screw, and the swinging arms E E E, connected with the sliding

plate and stick and pivoted on the strip D, all arranged substantially as shown and described.

In testimony that I claim the foregoing I have hereunto set my hand and seal.

WILLIAM W. GILMAN. [L. S.]
